UNITED STATES PATENT OFFICE.

JOHN BUFFELEN, OF TACOMA, WASHINGTON.

PORCH-COLUMN TURNING AND BORING MACHINE.

No. 904,044.

Specification of Letters Patent.

Patented Nov. 17, 1908.

Application filed August 31, 1906. Serial No. 332,819.

To all whom it may concern:

Be it known that I, JOHN BUFFELEN, a citizen of the United States of America, residing at Tacoma, in the county of Pierce 5 and State of Washington, have invented certain new and useful Improvements in Porch-Column Turning and Boring Machines, of which the following is a specification, reference being had therein to the accompanying 10 drawings.

This invention relates to machines for turning and boring porch columns from solid square timber, and has for its objects to provide improved means whereby the timber 15 may be held and rotated while it is being turned and bored; second, to provide removable intermediate supports for the column; and to give the squared timber its preliminary rough cut, its finishing cut and 20 bore out its core all at the same time. I attain these objects by the mechanism illustrated in the accompanying drawings, in which

Figure 1 is a front elevation of my machine showing a completed column mounted therein. Fig. 2 is an end elevation thereof. Fig. 3 is a vertical cross-section of one of the standards showing the parts arranged for allowing the column to be inserted or 25 withdrawn, and Fig. 4 is a similar view, showing the column held in place therein. Fig. 5 is a vertical longitudinal section of the rotating column holder and the upper part of the standard, and Fig. 6 is a plan 30 thereof. Fig. 7 is a vertical cross-section of the central part of my machine on the line 7—7 in Fig. 8 showing the rough cutter and the finishing back-knife. Fig. 8 is a front elevation of the central part of my 35 machine on a larger scale than Fig. 1, and Fig. 9 is a similar rear elevation thereof, both of said views showing the column one-half made.

Similar numerals of reference refer to 40 similar parts throughout the several views.

The frame of my improved machine consists of the two small end standards "1", the two larger intermediate or main standards "2" and the three joining tables "3". 45 The end standards "1" are shown in Figs. 1 and 2 and are made hollow. The central standards "2" are of similar construction, but are somewhat larger. These standards "2" are provided with sliding tops which 50 are fully described hereinafter. The tables "3" are shaped like inverted channel beams, 55 as clearly shown in Fig. 7. These tables are securely fastened to the standards and have their surfaces properly finished off to support and guide all of the longitudinally 60 movable parts of the machine.

The mechanism mounted on the frame above described may be classed and described as (1) mechanism for holding and rotating the square timber to be turned, (2) mechanism 65 for rough cutting it to shape, (3) mechanism for finishing the column, (4) mechanism for supporting the column while being turned intermediate of the main standards, and (5) mechanism for boring the core of the tim- 70 ber out.

Taking the first class of mechanism, as above enumerated, special reference may be made to Figs. 3, 4, 5 and 6, in which this mechanism is illustrated in detail. All of 75 this mechanism is in two duplicate sets, one in connection with each of the two standards "2", so that a description of one will be understood to apply to both sets. The top of the standard "2" is provided with two 80 grooves into which the dovetail tongues "4" on the bottom edge of the sliding tops "5", fit. The top of the standard "2" is provided with a central opening adapted to allow the hereinafter mentioned belt to have perfectly 85 free play therein. Semi-circular flanges "6" project inward from the sides of the standard "2" and surround semi-circular openings "7" therethrough, the said flanges being adapted to enter into the end cavities of the 90 column holder as shown in Fig. 5, and the said openings "7" being large enough to allow the square timber of the column to turn on its axis without touching the standard "2". A pair of bearing plates "8" are 95 adjustably bolted to the inner sides of the standard "2", as shown in Figs. 3, 4, 5, and 6, the bearing edges of said plates being concentric with the semicircular flanges "6" and spaced therefrom so as to bear below the 100 outer surface of the column holder, which is supported from downward movement thereby, and which is kept from upward movement by the said semicircular flanges "6" which enter the circular cavities in its ends. 105 The central axis of all the circles in this set of mechanism is the central transverse line of the top plane of the standard "2". As above indicated, the standard "2" is provided with a sliding top "5". This top is 110 made in two similar parts divided along the central vertical transverse plane, each part

being adapted to slide on the top of standard "2", from its innermost position outward, as shown in Figs. 4 and 3, respectively. The parts "5" are made hollow with a central belt hole "9" and with sides cut away at 5 "10", as shown in Figs. 3 and 5, to fit around the column holder and to allow the square timber of the column to rotate without touching it. The upper edges of the two parts "5" meet above the center of the column and are beveled off very slightly in opposite directions, as shown in Fig. 6. The parts "10" of the sliding tops "5" complete the bearings for the column holders and act in conjunction with the parts "6" and "8" above 10 described.

The sliding tops "5" are pressed into place by means of the levers "11" which are pivoted at "12" to the standard "2" and are connected by the link "13" to the foot lever "14", also pivoted to the standard "2". The levers "11" are arranged in the central plane of the standards and are shaped so as to pass from the outside into the inside thereof, the link "13" acting practically vertically under the center point of the standard. The lever "14" is made double, having two main arms, one under each standard "2", which are bent near their ends so that the ends come between the standard "2". A foot-board 15 "15" joins the ends of the levers "14". Thus by stepping on the board "15" all four of the levers "11" are pressed in pairs towards the central axis of the machine, each 20 pair engaging one of the column holders to complete the bearings therefor as above described. When the lever "14" is released, the tops "5" may be moved outward by hand, by weight, or by spring.

40 The column holder consists of a cylindrical body having a square axial hole therein adapted to receive the column. This body is supported by the above described devices and supports the column, and is itself rotated by a belt "16" which engages its central part and which passes through the holes made therefor in the standard "2" and the sliding top "5" as above described.

In order that a column may be inserted 45 and removed from the machine without removing the column holder, I have constructed it in the following manner: The main part "17" is semi-cylindrical in shape and has two of the sides of the square axial hole formed in it, the said sides being cut into the part "17" at angles of 45 degrees each to the plane thereof, thus cutting the said square hole at its longest diameter. Hinged to this part "17" are two opposite similar quarto-cylindrical parts "18" which complete the cylindrical form of the body when they are closed together, and which also at the same time complete the square axial hole there-through, but which open out from the body 55 "17", as shown in Fig. 3, in such a manner

as to open the square hole and to allow the square timber of the column to be inserted thereinto or withdrawn therefrom. These parts "18" can only be opened when the sliding tops "5" are withdrawn from contact therewith and they are locked into their closed position by the pressure of the sides "10" of said tops "5". Thus it will be seen that a square column timber may be moved into or out of the machine by raising the lever "14", which separates the parts "5", and by opening the quarto-cylindrical parts "18" of the holders.

The square timber having been mounted in the column holders and being rotated on the machine by the belts "16" the second set of mechanism next comes into consideration, namely, the mechanism for rough cutting it into shape. This mechanism is shown in Figs. 1, 7, 8 and 9. Referring principally to Fig. 7, it will be seen that the table "3" joining the two main standards "2" is provided with an overhanging lug "19" on its upper face, said lug running the entire length between the standards "2". A side bearing plate "20" also extends practically the entire distance between the standards "2". A carriage "21" rides on the table "3", bearing principally on the parts "19" and "20" and being held and guided thereby in its longitudinal motion along the central portion of the machine. This motion is obtained from the rotating feed screw "22" which extends from end to end of the machine and which drives the said carriage "21" and the two end boring carriages hereinafter described. The screw "22" passes through a suitable box "23" in the carriage "21" without touching the sides thereof and engages therein with a removable key 23^a 105 which may be brought into engagement therewith or withdrawn therefrom by the operator of the machine, thus allowing the said carriage to be moved on its tracks "19" and "20" independently of the screw "22". The key 23^a is rectangular in form and is provided at its outer end with a knob or handle 23^b and at its inner end with a segment of a screw-thread 23^c, which engages the thread of the screw 22 when the key is pushed into its engaging position, but which releases the screw 22 from all connection with the carriage 21 when the key is drawn out therefrom. A shaft "24," which is key-seated from end to end, is mounted in bearings in the standards "2" and extends from one of said standards to the other and is rotated by a belt "25" engaging a suitable pulley thereon. This shaft passes through two parallel upwardly extending ears of the carriage "21". The two arms "26" are mounted loosely on the shaft "24" between the two ears of the carriage "21", and are radially and longitudinally movable thereon. A gear wheel "27" is mounted on the shaft 115 120 125 130

"24" between the arms "26" being keyed thereto so as to rotate therewith, but being free to move longitudinally thereon with the carriage "21". A train of gears is mounted 5 between the arms "26" and meshes with the said gear "27", the last of said train carrying a rotating roughing tool "28", which moves longitudinally with the carriage "21" and is rotated by the shaft "24". The position 10 of this tool "28" relatively to the square timber of the column is varied so as to produce, in the rough, approximately the desired shape of the column. This is attained by means of the irregularly shaped guide 15 track "29", secured to the top of the table "3", which is engaged by a downward projection "30" secured to one of the arms "26". Thus as the carriage "21" moves longitudinally along the table, it carries with 20 it the rotating cutter "28" which is raised or lowered by the track "29" into or away from the rotating timber and thus varies the diameter thereof.

The third class of mechanism of this machine 25 consists of the devices for finishing the cutting of the column. To the inner sides of the main standards "2" are fastened, at a point slightly to the rear of the center, the two vertical guides "31" which 30 are provided at their upper ends with projections adapted to hold and form a bearing for the vertical feed screws "32" which are journaled therein and in the lower boxes "33" secured to the standards "2". These 35 feed screws "32" have bevel gears "34" at their lower ends, said gears meshing with bevel gears "35" mounted on a horizontal shaft "36" which is suitably mounted on bearings on the standards "2". The shaft 40 "36" is rotated by means of the sprocket chains "37" extending between suitable sprocket wheels mounted on the horizontal feed screw shaft "22" and on the shaft "36", as shown principally in Figs. 3 and 4, 45 the said sprocket mechanism being placed preferably within the hollow part of the standards "2". Thus the vertical feed screws "32" turn with the horizontal feed screw "22". The guides "31" are also provided 50 with vertical dovetail slots "38" into which the ends of the inclined rear bar "39" fit. This bar is preferably formed similar to a channel bar, but has enlargements near its ends through which the feed screws "32" 55 pass. A back knife "40" is secured to the rear bar "39" and is shaped so that by its vertical movement past the rotating column timber it will finish said column to its required design, the knife being made with 60 varying thickness in a horizontal plane to correspond with the varying diameter of the different parts of the column. The knife is slightly inclined as indicated in Figs. 2 and 7, so that after its cutting point at any section 65 has passed the horizontal plane of the

column, the upper part of the knife will not touch the column which is at that point in its finished condition. The whole knife is inclined at about 30 degrees so as to have a shaving action as well as a planing action 70 on the column as it comes in contact with it, and further, so as to cut said column continuously and successively from one end to the other, the point of cutting traveling slightly behind the rough cutter above described. 75

The fourth class of mechanism relates to devices for supporting the column, intermediate of its main supports in the standards "2". To the rear side of the channel table 80 "3" are secured the vertical guide lugs "41", in which freely slide the vertical supporting bars "42", shown in Figs. 7, 8 and 9, the said bars "42" being adapted to be raised into contact with the lower side of 85 the column as it is rotating and to support it by upward pressure thereon. These bars "42" are provided with side lugs "43" through which pass the adjusting set screws "44" and under which slides the horizontally longitudinally movable raising bar "45". This bar "45" rests on the table "3" and has its upper surface in two levels connected together by a curved inclined part. When the bar "45" is withdrawn (towards 90 the right in Figs. 1 and 8) both of the bars "42" rest on its lower level, but as it advances toward the left, the right-hand bar "42" is gradually raised by the inclined part until it touches the column (when it 95 rests on the upper level of the bar "45"). As the bar "45" travels farther, the right-hand bar "42" remains in contact with the column, and the left-hand bar "42" is raised into contact. The bar "45" is moved by a 100 bar "46" which is secured to the carriage of the right-hand boring mechanism hereinafter described. The bar "46" passes through the standard "2" (as shown in 105 Figs. 3 and 4) and engages in a horizontal slot "47" in the bar "45" (Fig. 9), so that said bar "45" will not need to move as far as does the said boring mechanism. The position of the inclined part of the bar "45" 110 is arranged so that the bar "42" will be raised immediately after the back knife "40" has passed the point where it will bear against the column; this is clearly shown in Figs. 8 and 9 in which the knife has just finished one-half of the column, 115 while the rough cutter is slightly in advance thereof.

The fifth class of mechanism in my machine 120 is a pair of boring or drilling tools to take out the core of the timber so as to render it lighter for shipping purposes. This mechanism is mounted on the ends of the machine and consists of stationary guides, or holders "48", secured to the 125 tables "3" close to the ends of the column 130

and through which the rotating boring tools "49" pass. These tools are provided with cutting or boring ends and screw shaped chip and dust removers. The tools "49" 5 are mounted at their outer ends in the carriages "50" which are somewhat similar in form to the carriage "21" and which are supported by the end tables "3" and are forced forward by the feed screws "22", 10 whose threads are cut in opposite directions so that the said carriages "50" approach each other during the process of boring the column. The carriages "50" also carry arms "51", which extend down and around 15 a slotted shaft "52" rotated by a belt "53". A pulley is carried on the shaft "52" between the arms "51" and is connected by the belt "54" to a pulley mounted on the tool "49". The shaft "52" extends from 20 end to end of the machine and rotates the tool "49" in every position thereof.

Thus it will be seen that after a column timber is inserted in the holders as above described and the machinery is set in motion; 25 the timber is rotated; the rough cutter is rotated and moved longitudinally, so as to bring the timber to approximately the required shape; the back knife is drawn down and finishes the column a few inches behind 30 the rough cutter; the intermediate support raising bar moves and raises first one and then the other of the supports into contact with the column; and the boring tools are forced into the two ends of the timber and 35 bore out its core.

Having, therefore, described my invention, what I claim is:

1. A column holder and rotating device comprising a cylindrical pulley, having a 40 shaped hole in its center adapted to fit the column, and being formed of one semi-cylinder and two complementary quarto-cylinders, each of said quarto-cylinders being hinged to opposite sides of the semi-cylinder; a belt engaging the center of said pulley and rotating it; and double bearings 45 engaging the pulley on each side of the belt, and each comprising a fixed semicylindrical lower portion in which the pulley rests and two complementary quarto-cylindrical upper portions completing said bearing and engaging the pulley, the two quarto-cylindrical portions on a side being formed in one casting and each casting being adapted to be 50 slid horizontally away from the axis of said bearing, whereby said bearing is opened and removed from over said quarto-cylindrical parts of the pulley and said parts may be opened to allow access to the hole in the 55 pulley.

2. A column holder and rotating device comprising a cylindrical pulley, having a shaped hole in its center adapted to fit the column, and being formed of one semi-

cylinder and two complementary quarto-cylinders, each of said quarto-cylinders being hinged to opposite sides of the semicylinder, 65 said pulley being recessed in its ends to form an annular flange at each end; a belt engaging the center of the pulley and rotating it; and double bearings engaging the pulley on 70 each side of the belt and each comprising a fixed semicylindrical lower portion in which the pulley rests, a concentric semicircular portion entering the said recess in the end of the pulley and engaging the lower inner edge of said annular flange to hold the pulley down, and two complementary quarto-cylindrical upper portions completing said 75 double bearings and engaging the outer surface of the pulley, the two quarto-cylindrical portions on a side being formed in one casting and each casting being adapted to be slid horizontally away from the axis of said bearing, whereby said bearing is opened and 80 removed from over said quarto-cylindrical parts of the pulley and said parts may be opened to allow access to the hole in the 85 pulley.

3. In a column turning machine, the combination of a supporting standard with semi-circular bearings formed therein; semicircular lugs concentric with said bearings, and of less radius, formed on said standard; oppositely sliding castings on said standard 95 each provided with complementary quadrant bearings completing the circles of said bearings; and a cylindrical openable column holder journaled in said completed bearings and having circular recesses in its ends engaged by said semicircular lugs on the standard, but being free from engagement with any part of said sliding castings. 100

4. In a column turning machine, the combination of a supporting standard with parallel co-axial semicircular bearings formed in its two sides, with belt-space therebetween, 105 said bearings being joined by the upper portion of said standard; guideways formed in the upper portion of said standard on each side of the axis of said bearings and at right angles thereto; two complementary castings mounted in said guideways and each provided with two parallel co-axial quadrant bearings, complementary to each 110 other and in the same vertical planes with the semicircular bearings, said quadrant bearings completing the circles of the two 115 bearings, with belt-space therebetween, and said castings being adapted to be slid in the guideways away from each other and from the bearing to permit the removal therebetween of the column from the column holder; and a single cylindrical column holder journaled in both of said bearings and extending 120 therebetween and adapted to be engaged and rotated by a belt between said bearings, 125 said column holder being formed of open-

able sections locked closed by the bearings when the bearings are completed but openable when the said castings are separated.

5. In a column turning machine, the combination of two separated parallel co-axial bearings; and a column holder mounted therein and extending therebetween, and having a cylindrical outside form when closed, and formed by a semicylindrical body
10 and two quarto-cylindrical bodies, each

hinged thereto but separated from each other and completing the cylinder with said semi-cylindrical body.

In testimony whereof I affix my signature in presence of two witnesses.

JOHN BUFFELEN.
